UNITED STATES PATENT OFFICE.

SAMUEL WILLIAMS OF NEW ORLEANS, LOUISIANA.

TAKE-UP FOR SEWING-MACHINES.

SPECIFICATION forming part of Letters Patent No. 634,785, dated October 10, 1899.

Application filed October 4, 1898. Serial No. 692,633. (No model.)

To all whom it may concern:

Be it known that I, SAMUEL WILLIAMS, a citizen of the United States, residing at New Orleans, in the parish of Orleans and State of Louisiana, have invented certain new and useful Improvements in Wax-Thread Sewing-Machines; and I do hereby declare the following to be a full, clear, and exact description of the invention, such as will enable others skilled in the art to which it appertains to make and use the same.

My invention relates to improvements in take-up devices for wax-thread sewing-machines, and especially to that class of machines known as "inseaming shoe-sewing" machines.

The object of my said invention is to render certain machines of this class now in use—such, for example, as the well-known Goodyear welt-sewing machine and others—capable of sewing as flat an inseam as may be done by hand and at the same time preserving the superior qualities of the chain-stitch. I attain these objects by the employment of a yielding mechanism in some portion of the take-up or thread-controlling mechanism acting upon the thread after it has left the tension-wheel, graduated approximately to the breaking strain of the thread, and by which as the thread is drawn near the completion of the stitch an ever-increasing strain is applied thereto until the maximum for which the device is adjusted is attained, thus avoiding any severe shock at the final pull and enabling a greater tension to be applied to the same size of thread than has hitherto been done. Likewise at the commencement of the return stroke the maximum strain is reduced gradually, thus completely setting the stitch and preventing any slip or relaxation thereof.

In order that my said invention may be more clearly understood, the same will be described with reference to the accompanying drawings, in which—

Figure 1 represents in side elevation, with portions removed, a forth of Goodyear welt-machine with my improved take-up mechanism applied thereto. Fig. 2 represents a detail plan view of the take-up-lever seat. Fig. 3 represents the auxiliary take-up lever in elevation. Fig. 4 represents in front elevation the machine and attachments shown in

Fig. 1 with parts removed. Fig. 5 represents in front elevation an enlarged detail view of the bracket for supporting the take-up-lever 55 sliding seat, and Fig. 6 represents the same in side elevation.

As the various working parts of the Goodyear welt-machine above referred to have been fully described in prior patents and as 60 their operation is well known in the art, only those parts which operate directly with or are embodied in my invention need be particularly herein referred to and described.

In the accompanying drawings similar parts 65 are represented by similar letters throughout the several views.

In the form of my invention shown in the drawings I mount the take-up lever E upon a stud e¹ and between the two lugs F and F' 70 of a sliding seat F². This sliding seat F² is provided also with a third lug F³, located at one corner thereof and at right angles to the lugs F and F', the lug F³ being provided with a stud or buffer f³. (See Figs. 1, 2, and 4.) 75

In line with the buffer f³ is the screw-threaded buffer f⁴, which is screwed into lug F⁴ on the stationary bracket H, the said bracket also comprising the slide-box h for the take-up seat F². Mounted on the buffer f⁴ is the adjustable stud or nut f⁵, between which and the lug F³ and coiled around the buffers f³ and f⁴ 80 is the tension-spring K, while at the rear end of the buffer is located the check-nut f⁶. The adjustable stud f⁵, with buffer f⁴ intact, limits 85 the play of the sliding seat F². A washer f⁷ may be inserted on the buffer f⁴, or a plurality of such washers may be so inserted, as may be desired, for varying the compressibility of the spring K. 90

The edge on the right side of the seat F² is beveled and fits into recess h', while the edge on the left side of said seat is similarly beveled to the bottom surface, so as to have a sliding fit between edges h' and h². A cap h³ 95 prevents any tendency of said take-up-lever seat to lift during its operation. It will be noticed that this cap h³ extends only about one-third of the length of sliding seat F²; but this is done for compactness, and is sufficient, 100 as the alignment of the various parts forming the take-up motion is such that the central line of force communicated by the take-up cam-lever passes through the center of the

core of spring K, which arrangement prevents any cramping of sliding seat in the slide-box in operation.

The method of interchanging the compression-spring is as follows: Loosen check-nut f⁶ and screw the stud f⁷ backward against F⁴, whereby the compression on spring K is entirely relieved, said spring being made just long enough to go in place without resistance 10 when the buffers come apart to their fullest extent. Then remove cap h³, Fig. 5, disconnect the connecting-rod from take-up arm C, and the take-up-lever seat can be readily lifted out of the slide-box and the compression-spring replaced by any other of suitable length and core.

The part h⁴ of the bracket H is steadied or braced by the continuation of the upright portion h⁵. A hollow space is formed in the bracket, as at h⁶, and the extension of the bracket is given a curved sweep to allow the shaping in metal to be done easier.

In adapting this invention to the Goodyear welt-sewing machine it will be seen that I alter several of the parts thereof. Thus instead of the ordinary bracket which supports the take-up cam-lever I employ the bracket H. I also employ a new looper-lever L, looper-lever swivel L', welt-guide-throw cam-lever M, alter 20 the hubs of the back-gage lock-cam lever N and needle-cam lever, take-up lever E, take-up cam-lever B, auxiliary take-up lever E', and studs for the same where necessary. The auxiliary take-up and take-up levers are provided with the thread-rollers e and e', respectively.

A desirable form of tension device for use in connection with my improved take-up is shown in Fig. 4. The tension-wheel D and 25 brake-lever P of this device are mounted in a bracket O, secured to the head of the machine, as at o. The tension-wheel D is mounted upon a stud d, carried by the rearwardly-extending portion o' of the bracket O. The 30 brake-lever is pivotally mounted upon a stud p, which is carried by the frames O and O', and embraces hubs p' and p² in its construction. A sleeve or washer d' is mounted next to the tension-wheel and on the stud d. This 35 stud projects out beyond the washer d', where it is provided with the thumb-nuts d³ and d⁴, between which and the said washer is inserted the coil-spring d¹, carried upon the projecting portion of the stud d. The other 40 end of the stud d is held in the frame by the nut d⁵. Secured to or integral with the tension-wheel and on the opposite side thereof from the washer d' is the drum D', upon which the brake-band Q acts. The 45 brake-band Q, preferably of leather, forms the lining of the steel band Q', which is secured at its upper end in a clamp q, which latter is pivoted, as at q', to the brake-lever p, while the other end of the steel band Q is secured, 50 as at q², to the lower end of the rod Q². A lug q³, having a central aperture, is secured by the nut q⁴ to the lower part of the cam-lever

in front of the connection q². The rod Q² passes up through the aperture of the lug q³, having the portion extending up beyond the lug screw-threaded. The nuts q⁵ are placed on the rod next to the upper side of the lug q³, while the extreme upper end of the rod carries the nuts q⁶, and inserted between the nuts q⁵ and nuts q⁶ is the coil-spring q⁷. By this arrangement the tension of the brake may be adjusted. Secured to the upper end of the bracket O is the cam-lever stud R, against whose eccentric periphery the tension-lever is held by the spring r, secured to the tension-lever, as at r', and to the stud r². The brake-lever is operated by a cam-block S, dovetailed into the periphery of the thread-finger cam S'. The thread T passes from the tension-wheel D to the thread-roller e², and thence to the rollers e and e' of the auxiliary take-up and take-up, and then to the needle G.

J represents the insole being operated upon. As shown in Figs. 1 and 4, the parts are represented in the relative positions that they would occupy just as the slack thread is taken up and fresh thread is to be pulled off of the tension-wheel. At this time, with sufficient pressure against the tension-wheel to hold the thread from paying out, and thus holding the long end of the take-up lever from continuing its upward movement, the backward motion of the cam-lever B in the direction of the arrow causes the lug F³ to advance toward the lug F⁴, compressing the 55 spring K until the buffers f³ and f⁴ meet, that is to say, when the take-up cam-lever begins its travel in the direction of the arrow it does not impart a positive upward movement to the outer end of the take-up lever, 60 but instead thereof causes the buffer f³ to advance toward the buffer f⁴, all the while compressing the spring K, the connection between the take-up cam-lever and the take-up lever acting as a kind of toggle-joint, thus 65 exerting a yielding stress on the thread until the buffers meet, when a positive upward movement of the take-up lever will then take place. There is thus an almost total pause in the drawing of the thread, the required 70 strain being fully distributed throughout the thread before drawn off the tension-wheel, which, according to the present arrangement, is capable of carrying a greater pressure than with devices heretofore constructed. The 75 tension brake-lever P is so adjusted as to clamp the tension-wheel at the moment that the required amount of thread is drawn off, and the cam-stud R is secured to the bracket O that the approach of the lever P to the cam S' may be varied. At the moment that the 80 brake is to be applied to the tension-wheel the cam-block S engages the upper end of the brake-lever, forcing it back. This causes the lower end of the brake-lever carrying the 85 brake-band to move forward, which obviously brings the brake-strap in engagement with the tension-wheel drum. The degree of the 90 tension or pressure of the brake-strap on the

drum is governed by the spring q^7 , the tension of which may be varied by the adjusting-nuts q^6 .

In regard to the adjustment of tension it will be noticed that by my invention springs of different degrees of compressibility may be interchanged or the compressibility varied by the insertion or removal of washers. The tension of the spring may also be varied by the adjusting-nut f^5 . This feature, which admits of the tension of the take-up and tension devices being so readily adjusted, is a most advantageous one, inasmuch as by it the machine may be used with any size of thread from that required for the smallest baby-shoe to that required for the heaviest work, and all the while utilizing the full strength of the thread. Besides the superiority of the work thus produced there will be a reduction in the time lost which would otherwise be occasioned by the breaking of the thread.

While I have herein shown and described my invention as applied to a Goodyear welt-sewing machine, the said invention is, nevertheless, applicable to all sewing-machines using take-up mechanism to tighten the stitch independently of the needle. An auxiliary take-up is usually employed in machines of this character to take up the slack thread as the take-up returns in the forming of a new stitch, and incidentally and to some slight degree it lessens the shock to the thread when a new supply is pulled from the tension-wheel in completing the stitch; but the two functions are different and require different conditions. An auxiliary take-up requires a considerable throw and a spring with sufficient flexibility to exercise its usefulness throughout that space, whereas the function of gradually applying strain to the thread requires but a short space for operation with a spring of rapidly-increasing resistance.

I do not limit myself to the described details of mechanism here shown relative to a yielding mechanism embodying the principles herein set forth, as these principles can be made operative by other suitable mechanism and in any portion of the take-up or thread-controlling mechanism without departing from the spirit of my invention.

Having thus described my invention, what I claim, and desire to secure by Letters Patent of the United States, is—

55 1. In a sewing-machine, the combination with a stitch-forming mechanism comprising a needle and tension device, of a take-up lever and means for actuating the same, a yielding support to which said lever is pivoted, said yielding support, during the operation of the take-up exerting a yielding stress upon the thread between the tension device and the needle and being so adjusted that its full

stress upon the thread is approximately equal to the maximum strength of the thread, the 65 said support operating independently of the needle and exerting its greatest stress just prior to the drawing off of fresh thread for the formation of a new stitch, substantially as described.

70 2. In a sewing-machine, the combination with the take-up cam-lever and take-up lever and operative connection between the same, of a yielding mechanism actuated by said take-up cam-lever and the take-up lever comprising two members connected together, one of said members being movable relative to the other, a spring interposed between the said members, an adjusting-nut for varying the tension of said spring and means for interchanging the said springs, substantially as described.

75 3. In a sewing-machine, the combination with the take-up cam-lever and means for operating the same, of a take-up lever and means connecting the same with the cam-lever, a yielding support to which said take-up lever is pivoted, comprising two members connected together, one of which is movable relative to the other, a spring interposed between the said members and means for adjusting the tension of said spring substantially as described.

80 4. A sewing-machine, comprising a take-up mechanism including a take-up cam-lever and a take-up lever, a sliding seat upon which said take-up lever is mounted, a stationary bracket carrying said sliding seat, a resilient body interposed between said sliding seat and the stationary bracket, substantially as described.

85 5. A sewing-machine, comprising a take-up mechanism including a take-up cam-lever and a take-up lever, a sliding seat upon which said take-up lever is mounted, a stationary bracket carrying said sliding seat, a resilient body interposed between the said sliding seat, and the stationary bracket, and means for adjusting the tension of the said resilient body, substantially as described.

90 6. A sewing-machine, comprising a take-up mechanism including a take-up cam-lever and a take-up lever, a sliding seat upon which said take-up lever is mounted, a stationary bracket carrying said sliding seat, a buffer carried by said sliding seat and a buffer carried by said stationary bracket, a resilient body interposed between said buffers, and means for adjusting the tension between said buffers, substantially as described.

95 In testimony whereof I affix my signature in presence of two witnesses.

SAMUEL WILLIAMS.
